UNITED STATES PATENT OFFICE.

JOHN A. WILLNERS, OF PHILADELPHIA, PENNSYLVANIA, ASSIGNOR TO PENN
UTILITY COMPANY, OF CONSHOHOCKEN, PENNSYLVANIA, A CORPORATION OF
DELAWARE.

LOCKING DEVICE FOR CLOSURES.

Application filed April 1, 1925. Serial No. 20,019.

My invention relates to improvements in locking devices for closures, the object being to provide locking means that shall be simple and substantial, that shall not be injuriously affected by weather conditions, or by moisture or by foreign substances, or in other words that shall be capable of hard usage without liability of getting out of order. The invention also comprises means for reducing to a minimum the danger of accidentally leaving the closure unlocked. In securing this much desired object, the parts are so arranged that the closure cannot be brought into complete closing position, which condition is plainly visible,—without first turning the locking element into the unlocking position, and furthermore the provision that the tool for so actuating the locking element, cannot be withdrawn therefrom, without first returning the locking element into the locking position, all of which will be herein specifically described.

Referring to the drawings, which illustrate, merely by way of example, a suitable embodiment of my invention;—

Fig. 1 is a plan view.

Fig. 2 is a front elevation with the closure partly open.

Fig. 3 is a plan of the underside of the lug connected to the closure.

Fig. 4 is a section on line 4, 4 of Fig. 3.

Fig. 5 is a plan of the lug connected to the collar or stationary part.

Fig. 6 is a section on line 6, 6 of Fig. 5.

Fig. 7 is a section through lugs 19 and 28 on line 7, 7 of Fig. 3 when the parts are locked in closed position.

Fig. 8 is a side elevation of the actuating tool.

Fig. 9 is a fragmentary front elevation of lower end of same.

Fig. 10 is a plan of same.

Similar numerals refer to similar parts throughout the several views.

My invention is herein shown, merely by way of example, as applied to the filling pipe for an oil tank or the like.

On to the top of the filling pipe 15, is threaded the collar 16, to which is hinged, as at 17, the cap or closure 18. This closure 18 is provided with the lug 19, having at its front end the arc-shaped formation 20, channelled as to its inner side, and the projection 21 spaced therefrom. Between these formations 20 and 21 is provided a channel seat 22 for the element or shaft 23, and the compres-

sion spring 24, engaging the rear end of shaft 23. This shaft 23 is provided with the L-shaped pin or arm 25, projecting first at right angles from an intermediate part of shaft 23, and having its extreme end extending parallel with said shaft 23. At the outer end of shaft 23 is provided the triangular formation 26. The underside of lug 19 is chambered, as at 27, see Fig. 3, to permit the element 25 to enter the same when the shaft 23 is pushed in against the spring and then rotated.

The collar 16 is provided with a lug 28 registering approximately with lug 19, and having a chamber 29 in its upper side and a recess 30 in the front wall thereof for receiving the end of member 25. A block formation 31 is provided above the recess 30 having an inclined lower edge for engaging and guiding the end of pin 25. An operating tool 32 is provided with an engaging end 33, at right angles with the main extension of said tool, having the head 34 provided with the triangular recess 35 on its face. This triangular recess is adapted to fit upon the triangular formation 26 of shaft 23. An inclined lug 36 is also provided on the periphery of head 34 for engaging in the arc-shaped channel of formation 20.

In operation.—When the cap or closure 18 is locked in the closed position, the end of member 25 projects into the hole or recess 30 of lug 28, and the triangular end 26 of shaft 23 is in such position that the tool can be fitted into same. When it is desired to open the closure, the end of tool 32 is fitted onto said triangular end 26, and the tool is then pressed to force the shaft in against the tension of spring 24, until the lug 36 comes into alignment with the channel in the arc-shaped formation 20. Meanwhile the end of member 25 has been withdrawn from the hole 30, by the longitudinal inward movement of shaft 23, against the spring 24. The tool is then turned to the right, or clockwise direction; the said channel holding the shaft in the pressed-in position, so that the end of pin 25 may clear the inclined block 31 as the shaft is rotated in clockwise direction. When the end of pin 25 clears the inclined block 31, and moves into the chamber 27 of lug 19, the closure or cap 18 is free to move into the open position.

It will be noted however, that before the tool 32 can be disengaged from the triangular

end 26 of shaft 23, it must first be brought back into initial position, that is with the pin 25 in the locking position, although the lugs 19 and 28, may be separated as shown in Fig. 2.

When it is desired to close, and lock the closure 18 in closed position, it is necessary to engage the tool 32 with triangular end 26 and to perform the unlocking operation as 10 above described. The closure 18 is then brought into the closed position as in Fig. 7, and then by reversing the movement of the tool, that is operating it in the counterclockwise direction, the shaft 23 is rotated to carry 15 the end of pin 25 under the inclined block 31, which insures the complete closing of the cap 18, and then when the end of pin comes into 20 register with the hole 30, the lug 36 having meanwhile cleared the channel in formation 20, the shaft responding to the pressure of spring 24 moves forward to initial position and the end of pin 25 enters the hole 30, thus 25 locking the closure or cap in closed position in which position of shaft 23, as above indicated, the tool 32 can be disengaged from the end 26 of shaft 23.

What I claim is:—

1. In combination with a closure, a fixed formation and a movable formation, a key operated locking element seated in one of said formations having both rotative and longi-

tudinal movement therein and adapted to be brought into locking relation with the other formation and means for permitting engagement of the key with and disengagement of the key from said locking element only when 35 said locking element is in locking position.

2. In combination with a closure, a fixed formation and a movable formation, a key operated locking element seated in one of said 40 formations having both rotative and longitudinal movement therein and adapted to be brought into locking relation with the other formation, and means for preventing the disengagement of the key from the locking element except when the locking element is in 45 locking position.

3. In combination with a movable pipe cap, locking means therefor comprising a movable formation and a fixed formation, a key operated locking element associated with 50 one of said formations having both rotatable and longitudinal movement with respect thereto, a spring active in respect to said longitudinal movement, said locking element adapted to be brought into locking engagement with the other formation, and an arcuate formation adapted to prevent removal of the key from the locking element except when the locking element is in the locking position. 55

JOHN A. WILLNERS.
